NOZZLE TESTER

Abel J. Cole, Chicago, Ill., assignor to The Buda Company, Harvey, Ill., a corporation of Illinois

Application July 25, 1945, Serial No. 606,983

10 Claims. (Cl. 73—119)

1

My invention relates to nozzle testers and is more particularly concerned with nozzle testers of the type used to test nozzles for Diesel engines. My invention is an improvement over the nozzle tester disclosed in Gormley Patent No. 2,183,189 of December 12, 1939, owned by the assignee of this application.

An object of my invention is to provide a new and improved nozzle tester which is adapted to test a wider variety of nozzles than the apparatus of the prior art.

Another object of my invention is to provide a new and improved nozzle tester which enables an operator to test with facility a wider variety of characteristics than the apparatus heretofore in use.

Another object of my invention is to provide a new and improved nozzle tester which will readily test injection pressure, valve operation, spray pattern, and tightness of joints between various sections of the nozzle itself.

Another object of my invention is to provide a new and improved nozzle tester which can be readily adjusted to meet any or all of the foregoing tests.

Another object of my invention is to provide a new and improved nozzle tester which may be readily adjusted to operate with all of the various conventional types of nozzles commonly in use.

Other objects and advantages will become apparent as the description proceeds.

In the drawings:

Fig. 1 is a perspective view of a particular arrangement of nozzle testing apparatus embodying my invention;

Fig. 2 is a side elevation of a nozzle testing cradle with a nozzle mounted therein and the various parts constructed and arranged to test the nozzle for leakage between various sections of the nozzle itself;

Fig. 3 is a view similar to Fig. 2 but showing the apparatus set up to test the spray pattern of a nozzle;

Fig. 4 is an end view of the apparatus shown in Fig. 3 and indicating in phantom the manner in which the nozzle is supplied with fuel oil under pressure;

Fig. 5 is a top plan view showing a different type of nozzle block fixture and showing the manner in which this fixture is applied to a nozzle indicated in phantom;

Fig. 6 is a side elevation of the apparatus shown in Fig. 5;

Fig. 7 is a transverse section taken on the line 7—7 of Fig. 6;

2

Fig. 8 is a plan view of a portable mounting base;

Fig. 9 is a sectional view taken on the line 9—9 of Fig. 8;

Fig. 10 is a side elevation looking in the direction of the arrows 10—10 in Fig. 8;

Fig. 11 is an irregular section through the nozzle block and supporting structure of Fig. 2 and is taken on the line 11—11 of that figure.

In Fig. 1, I have illustrated a conventional arrangement of nozzle testing apparatus comprising a portable mounting base A, a nozzle supporting cradle B, a combined fuel oil reservoir and high pressure pumping unit C and a spray pan D. The unit C has a filling opening 20 through which the reservoir 22 is filled with fuel oil and a high pressure pump 24 operated by a handle 26 which delivers fuel oil under pressure to a fitting 28 located on the top of the reservoir 22. The fitting 28 is provided with a nipple 30 to which a flexible pipe 32 may be attached. A high pressure gauge 34 is mounted on the upper end of the fitting 28 and communication between the fitting and gauge is controlled by a valve which is moved to open or closed position by a handle 36.

Fuel discharged by the pump 24 flows through flexible pipe 32 to a low pressure gauge 38 and a rigid pipe 40 threaded into an appropriate opening in the nozzle 42 which is mounted in the cradle B for test purposes. The spray pan D is adapted to catch the fuel discharged from the nozzle 42 and to retain this fuel throughout the test and until the pan is emptied by the operator. In this way fuel oil sprayed from the nozzle is confined instead of being permitted to accumulate on the bench or other support on which the test is performed. The spray pan D is adjustably and removably supported on an upright pin 44 attached to the portable base A.

Referring particularly to Figs. 8, 9, and 10, it will be seen that this portable base A comprises a sheet metal platform 46 having supporting legs 48 drilled as indicated at 50 to receive screws, bolts, or any other suitable means for attaching the mounting base A to a bench or support as desired. It is not essential that this base be so attached to the bench or other article on which the test is conducted as operation of the high pressure pump 24 and other parts of the testing apparatus do not require that the base A be firmly attached to a bench or other support.

On the upper surface of the platform 46 there is welded, or otherwise suitably attached, a sheet metal receiver 52 having upturned and inwardly flanged edges 54 adapted slidably to receive the

pedestal portion of the cradle B. A stop 56 formed by turning up one end of the receiver 52 is preferably provided to limit the extent to which the cradle pedestal may be slid into the receiver 52. A generally similar receiver 58 is provided for the combined reservoir and pumping unit C, and this receiver 58 is provided with a stop 60 to limit insertion of the reservoir and pumping unit.

Referring particularly to Figs. 2, 3, and 4, it will be seen that the cradle B has a base or pedestal 62 and outwardly flaring sides 64 and 66 defining a nozzle receiving opening 68. The lower portion of the opening 68 is V-shaped and the nozzle is firmly held against the outwardly flaring portions of the sides 64 and 66 by a screw 70 threaded into the top portion 72 of the cradle B and rotated to clamping or non-clamping position by a suitable handle 74.

The pedestal of the cradle B is provided with a horizontal bore 76 for slidably receiving a rod 78 that is clamped in adjusted position by a set screw 80. A handle 82 is pivoted to the rod 78 at 84 and an anvil 86 may be moved up or down on the handle 82 and secured in adjusted position by a set screw 88. The end of the anvil 86 has a rounded nose 90 adapted to engage the cam operated pump 92 of a nozzle of the so-called unit type, that is, a nozzle having a cam operated pump as a unitary part of the nozzle structure.

When it is desired to test the nozzle to determine if there is any leakage in the joints between the several sections of which the nozzle is constructed, a nozzle block fixture is used to block the outlet of the nozzle. In Fig. 2 there is shown a nozzle block fixture comprising a sleeve 94 which is slidable on the rod 78 and secured in place by a set screw or thumb screw 96. The sleeve 94 has an upward extension 98 provided with an elongated slot 100 (Fig. 11) slidably receiving a threaded nozzle block 102 having flattened sides 104 which prevent rotation of the block in the slot 100. The block 102 has a nozzle receiving recess 106 and is adapted to be screwed firmly against the nozzle by a nut 108 which presses against the vertical extension 98. A washer 110 is attached to the other end of the nozzle block by a screw 112 threaded into a tapped hole in the nozzle block and this washer prevents the nozzle block from becoming separated from the sleeve 94.

In testing some nozzles, it is preferable to use a different type of nozzle block fixture, and in Figs. 5, 6, and 7, I have shown an alternative form of nozzle block fixture. The nozzle block fixture of Figs. 5, 6, and 7 has a generally U-shaped frame 114 having inturned ends 116 and 118 adapted to engage behind a collar 120 provided by the nozzle 122 shown in phantom in these figures. An arc shaped strap 124 overlies the nozzle 122 adjacent the inturned ends 116 and 118 and prevents spreading of these ends at the same time it prevents the fixture from falling off the nozzle 122.

The fixture includes a nozzle block 126 having a recess 128 for receiving the discharging end of the nozzle. The block 126 is held in sealing engagement with the end of the nozzle by a thumb-screw 130.

In performing a spray test on a unit type of nozzle, the nozzle is mounted in the cradle B as indicated in Figs. 1, 3, and 4. The handle 26 of the reservoir and pumping unit C is operated until the low pressure gauge 38 shows a moderate pressure, of say 50 lbs. per square inch. The popping lever or handle 82 is then operated

sharply to open or "pop" the check valve and cause a spray at the nozzle. If no spray appears, the nozzle is clogged and should be removed and cleaned. If spray appears, the shape of the spray can be carefully observed for several operations of the popping lever to determine if this spray has the proper shape or forms the proper pattern. The spray pan D can be used to collect and receive the spray as this pan has an inturned edge 132 which permits the spray pan to retain the fuel oil discharged in a series of tests.

To determine whether the nozzle has the correct opening hydraulic pressure, the handle 26 is operated slowly until the nozzle "pops" open. 15 In performing this test the operator should watch the high pressure gauge 34 carefully to determine the exact pressure at which opening occurs and this opening pressure should be compared with the data supplied by the nozzle manufacturer.

The nozzle may be checked for dribble or leaks by again operating the fuel pump 24 until pressure on the gauge is just below the opening pressure and checking the dribble or leaks at any point on the nozzle structure.

20 The pressure drop or closing point of the nozzle valve may be tested by operating the pump 24 slowly until the nozzle "pops." The handle 36 is then rotated quickly to close the gauge valve, and the operator watches the drop in pressure on the gauge until the nozzle snaps shut. The pressure at which this occurs should be compared with the data supplied by the manufacturer.

25 In using a nozzle block fitting to check leakage in the nozzle, either the fitting shown in Figs. 2 and 11 or the fittings shown in Figs. 5, 6, and 7 may be used. In either case the block is adjusted to exert enough pressure on the nozzle to block the orifice in the nozzle cup. The handle 26 is operated to create enough pressure to open the fuel inlet tube valve in the nozzle and then the popping lever 82 is operated with strong, sharp strokes to create a high hydraulic pressure in the nozzle while the operator inspects the nozzle structure for leaks at joints between the several parts of which the structure is formed.

30 The foregoing are typical examples of types of tests for which my novel apparatus is designed. The tests hereinabove described are not the only tests which can be performed with my apparatus, and numerous other tests may be devised for the various types of nozzles in use. It is also to be understood that my nozzle testing apparatus need not be mounted on a portable base like the base A shown in Figs. 1, 8, 9, and 10, but may be placed directly on a bench or other supporting structure. It is further to be understood that my invention is subject to numerous changes and includes all modifications and variations coming within the scope of the appended claims.

35 60 I claim:

1. Nozzle testing apparatus of the class described, comprising a portable base, a combined fuel oil reservoir and pumping unit mounted on said base, a nozzle supporting cradle mounted 45 on said base, means for removably securing a nozzle in said cradle for test purposes, means for connecting said pump with said nozzle, means carried by said cradle for operating pumping mechanism associated with a nozzle under test, and means adjustably carried by said cradle for blocking the discharge outlets of a nozzle under test.

2. Nozzle testing apparatus of the class described, comprising a fuel oil reservoir, a fuel oil 50 pump supplied from said reservoir, a cradle for

supporting a nozzle under test, means for removably securing a nozzle in said cradle for test purposes, means for connecting said pump with a nozzle being tested, adjustable means carried by said cradle for actuating pumping mechanism in a nozzle under test, and nozzle blocking means adjustably carried by said cradle.

3. Means for supporting and testing the nozzle of a Diesel engine, comprising a cradle having a pedestal and an opening for receiving a nozzle to be tested, means for removably clamping said nozzle in said opening, a rod adjustably secured to said pedestal, a nozzle pump actuating means attached to one end of said rod, and nozzle blocking means adjustably attached to the other end of said rod.

4. Nozzle testing apparatus of the class described, comprising a fuel oil reservoir, a fuel oil pump connected to said reservoir, a cradle for supporting a nozzle under test, means for connecting said pump with said nozzle, nozzle pump actuating means mounted on said cradle, means for removably securing a nozzle in said cradle, and means for blocking said nozzle.

5. Nozzle testing apparatus of the class described, comprising a fuel oil reservoir, a fuel oil pump supplied from said reservoir, a cradle for supporting a nozzle under test, means for removably securing a nozzle in said cradle for test purposes, means for connecting said pump with a nozzle being tested, adjustable means carried by said cradle for actuating pumping mechanism in a nozzle under test, a handle for said last means, and nozzle blocking means adjustably carried by said cradle.

6. Apparatus for testing a nozzle of a Diesel engine, comprising a cradle having a supporting pedestal and a nozzle receiving portion, means for removably clamping a nozzle in said cradle, a rod slidably mounted in said cradle, means for clamping said rod in adjusted position, a sleeve adjustable on said rod, means for securing said sleeve to said rod, an upright arm rigid with said sleeve, said arm having a slot therein, a nozzle block non-rotatably mounted in said slot, and threaded means for pressing said nozzle block against a nozzle.

7. Nozzle testing apparatus of the class described, comprising a portable base, a nozzle supporting cradle mounted on said base, means for removably securing a nozzle in said cradle for test purposes, means carried by said cradle for operating pumping mechanism associated

with a nozzle under test, and means adjustably carried by said cradle for blocking the discharge outlets of a nozzle under test.

5 8. Nozzle testing apparatus of the class described, comprising a cradle for supporting a nozzle under test, means for removably securing a nozzle in said cradle for test purposes, adjustable means carried by said cradle for actuating pumping mechanism for a nozzle under test, and nozzle blocking means adjustably carried by said cradle.

10 9. Apparatus for testing a nozzle of a Diesel engine, comprising a cradle having a supporting pedestal and a nozzle receiving portion, means for removably clamping a nozzle in said cradle, a rod slidably mounted in said cradle, means for clamping said rod in adjusted position, a sleeve adjustable on said rod, means for securing said sleeve to said rod, an upright arm rigid with said sleeve, means for securing a nozzle block to said arm, and means for pressing said nozzle block against said nozzle.

15 10. Apparatus for testing a nozzle of a Diesel engine, comprising a cradle having a supporting pedestal and a nozzle receiving portion, means for removably clamping a nozzle in said cradle, a rod slidably mounted in said cradle, means for clamping said rod in adjusted position, a sleeve adjustable on said rod, means for securing said sleeve to said rod, an upright arm rigid with said sleeve, said arm having a slot therein, a nozzle block nonrotatably mounted in said slot, means for vertically adjusting said nozzle block in said slot, and threaded means for pressing said nozzle block against a nozzle.
